(57) **CLAIM**

The ornamental design for a device for varying range of motion for barbell exercise, as shown.

DESCRIPTION

FIG. 1 illustrates a perspective view of a device for varying range of motion for barbell exercise.

FIG. 2 illustrates a front view of the device for varying range of motion for barbell exercise.

FIG. 3 illustrates a rear view of the device for varying range of motion for barbell exercise.

FIGS. 4 and 5 illustrate side views of the device for varying range of motion for barbell exercise.

FIG. 6 illustrates a top view of the device for varying range of motion for barbell exercise; and,

FIG. 7 illustrates a bottom view of the device for varying range of motion for barbell exercise.

The broken line showing is included for the purpose of illustrating environmental structure and forms no part of the claimed design.
